UNITED STATES PATENT OFFICE.

ROBERT PEEL AND THOMAS FREDERICK SHEVELS, OF NEW BRANCEPETH COLLIERY,
ENGLAND.

COKE-OVEN DOOR.

1,276,107.

Specification of Letters Patent. Patented Aug. 20, 1918.

Application filed September 19, 1917. Serial No. 192,067.

To all whom it may concern:

Be it known that we, ROBERT PEEL and THOMAS FREDERICK SHEVELS, both subjects of the King of Great Britain and Ireland, and both residents of New Brancepeth Colliery, in the county of Durham, England, have invented certain new and useful Improvements in or Relating to Coke-Oven Doors, of which the following is a specification.

This invention relates to coke ovens, and especially to doors for coke ovens. The object of this invention is to provide an improved door and means for supporting and protecting the coke oven end walls.

In accordance with this invention a cast iron frame is permanently fitted against the end of the oven so as to cover the ends of the dividing walls, the upper part or web 20 of the frame extending from wall to wall.

The upper part of the frame is or may be recessed and is or may be provided with an aperture adapted to be closed by a door pivoted to the frame, or by a removable plug.

25 The lower part of the frame forms a support to the oven door.

Referring to the drawings filed here-with:—

Figure 1 is an elevation of one form of door made in accordance with this invention;

Fig. 2 is a cross-section on line 2—2, Fig. 1;

Fig. 3 is a cross-section on line 3—3, Fig. 1; and

Fig. 4 is a vertical section on line 4—4, Fig. 1.

At the ends of the dividing walls *a a* is mounted a frame *b*. In the upper part of the frame is a flanged aperture *c* adapted to be closed by a door *d* hinged at *e* to the frame *b*. The door is provided with a flange *f*, adapted to hold fire-brick lining.

The lower part of the frame is provided 45 with a reveal *g g* which incloses the ends of the walls *a a*. The door *h* is provided with flanges *h'* which closely fit against the reveals *g g*. These reveals *g g* and the flanges *h'* slope inwardly on the top 50 and two sides so that the door fits the reveals as a wedge, the door sinking into the recess formed by the reveals sufficiently to form a ledge *h²* adapted to hold a luting of clay. The door is adapted to be lined with

firebrick so that the flanges *h'* and reveals *g* 55 are sandwiched between brickwork which keep the door and frame at an even temperature so that they will not become distorted and cracked. The door is provided with a link *j* by which it can be raised or lowered 60 into position.

In front of the frame *b* are disposed vertical angle iron standards *k* to which are secured cross rods *m m*, which coact with inclined planes *o o*, disposed in the door for 65 the purpose of holding the same in position in the frame *b*.

The door is adapted to be lined with fire-brick.

The upper door *d* when provided is 70 adapted for use for the purpose of leveling the coal charge. The lower door is large enough to enable the coke to be discharged.

A door made in accordance with this invention can be readily lifted without damaging the brickwork. The frame gives support and protects the coke oven end walls. The lifting door being lined gives protection to the charge and prevents what is known as "blackends".

80 The lifting door can be readily replaced should it become fractured. As the door fits into a frame it can be readily luted and rendered gas or air tight.

What we claim as our invention, and desire to secure by Letters Patent is:—

1. In coke ovens having dividing walls, a door frame permanently fitted against the end of the oven so as to inclose the end of the dividing walls, a web to said frame extending from wall to wall, inwardly inclined reveals to said frame, a lifting door, inwardly inclined flanges to said door adapted to hold a firebrick lining, said flanges and reveals being sandwiched between brick-work, and means for lifting said door in and out of position.

2. In coke ovens having dividing walls, a door frame permanently fitted against the end of the oven so as to inclose the ends of the dividing walls, a web to said frame extending from wall to wall, an aperture in said web, means for closing said aperture, inwardly inclined webs to said frame, a lifting door, inwardly inclined flanges to said door adapted to fit said reveals, and adapted to hold a firebrick lining, said flanges and reveals being sandwiched be-

tween brickwork, and means for lifting said door in and out of position.

3. In coke ovens having dividing walls, a door frame permanently fitted against the 5 end of the oven so as to inclose the end of the dividing walls, a web to said frame extending from wall to wall, inwardly inclined reveals to said frame, a lifting door, inwardly inclined flanges to said door adapted 10 to hold a firebrick lining, said flanges and reveals being sandwiched between brick-work, and means for lifting said door in and

out of position, standards in front of said door frame, cross rods between said standards, inclined planes in said lifting door 15 adapted to coact with said cross rods.

In testimony whereof we have signed our names to this specification.

ROBERT PEEL.

THOMAS FREDERICK SHEVELS.
